LUM A. LIM, OF NEW YORK, N. Y.

REVERSING MECHANISM.

1,054,220.

Specification of Letters Patent. Patented Feb. 25, 1913.

Application filed October 27, 1911. Serial No. 657,052.

To all whom it may concern:

Be it known that I, LUM A. LIM, a subject of the Emperor of China, and residing at New York, in the county of New York and State of New York, have invented certain new and useful Improvements in Reversing Mechanism, of which the following is a specification, such as will enable those skilled in the art to which it appertains to make and use the same.

This invention relates to laundry machines designed for use in washing garments or clothes of various kinds and classes, also other fabric articles such as bed clothing, table covers and other household supplies, and the object thereof is to provide a machine of this class which is simple in construction, efficient in operation and which will not injure the articles to be washed; and with this and other objects in view the invention consists in a machine of the class specified, constructed as hereinafter described and claimed.

The invention is fully disclosed in the following specification, of which the accompanying drawing forms a part, in which the separate parts of my improvement are designated by suitable reference characters in each of the views, and in which:—

30 Figure 1 is a side elevation of my improved laundry machine with part of the construction broken away and part shown in section; Fig. 2 a vertical section on the line 2—2 of Fig. 1; Fig. 3 a vertical section on the line 3—3 of Fig. 1; Fig. 4 a sectional detail view on an enlarged scale of the clutch mechanism and gear shown at the right of Fig. 1; Fig. 5 a sectional detail view on an enlarged scale of the reversing 40 device shown in Fig. 1; Fig. 6 a sectional detail view on an enlarged scale of a clutch mechanism shown at the left of Fig. 1, and; Fig. 7 a perspective view on an enlarged scale of the operative parts shown in Fig. 3 45 detached or disconnected.

In the practice of my invention I provide a receptacle *a* which is preferably oblong in form and substantially tub-shaped in transverse vertical section and for the purpose of this description the side *a*² of said receptacle will be called the back side thereof and the side *a*³ the front side thereof, and said receptacle is preferably supported on legs *a*⁴.

55 Mounted in the receptacle *c* is a rotary drum *b* in which the articles *c* to be washed

are placed and said drum is preferably composed of staves provided with perforations *c*² through which the water is free to pass, and in one side thereof is a door *c*³ which 60 may be held in place in any desired manner, and which is also preferably composed of perforated staves connected by transverse plates *c*⁴ on the inner side thereof, and said door may be held in position by means of 65 cleats *c*⁶ pivoted to the drum at *c*⁷, or the connection of the door with the drum may be made in any desired manner. The ends of the drum are closed by heads *c*⁸ in the usual manner and said heads are provided 70 centrally with trunnions having suitable bearings *c*⁹ in the ends of the receptacle *a*, and connected with one of said trunnions is a gear *d* by which said drum is rotated.

At the top of the left end of the receptacle *a* is supported a shaft *d*² which is mounted in a bracket *d*³ secured to said end of the receptacle and one end of which is also provided with a bearing *d*⁴ secured to 75 said end of the receptacle, and the shaft *d*² is provided with a pinion *d*⁵ which meshes with the gear *d*, and said shaft is also provided with two belt wheels *d*⁶ and *d*⁷ which are secured thereto.

At the back of the machine and formed in connection with the back legs *a*⁴, in the form of construction shown, are brackets *e* and mounted in said brackets centrally thereof is a horizontal shaft *f*, that portion of which between said brackets is provided with reverse threads. The ends of the shaft *f* project beyond the brackets *e* and the right hand end thereof is provided with a clutch sleeve member *g* which is secured thereto and inwardly of which is mounted a drive 90 wheel *g*² having a hollow clutch hub *g*³ adapted to receive the clutch sleeve member *g*. The inner end of the hub of the drive wheel *g*² is also provided with a clutch member *g*⁴, and said shaft *f* is provided inwardly of the drive wheel *g*² with a gear *g*⁵ 95 which is rotatable thereon and is provided with a clutch member *g*⁶ which corresponds with the clutch member *g*⁴. The wheel *g*² is moved longitudinally of the shaft *f* by a lever *g*⁷ pivoted at *g*⁸ and provided with a yoke *g*⁹ operating in a groove *g*¹⁰ in the clutch member *g*³ of the wheel *g*².

In the form of construction shown, a wringer *h* is secured to the back top edge 110 of the receptacle *a* and is provided with an operating shaft *h*² having a gear *h*³, and

mounted on the gears h^3 and g^5 which are preferably ordinary sprocket gears is a drive chain h^4 .

Mounted horizontally below the shaft f is a longitudinally movable clutch-operating rod i the left hand end of which is connected at i^2 with a clutch yoke i^3 the arms i^4 of which support similar clutch members i^5 and i^6 which are slidably mounted on the shaft f and between which are drive wheels i^7 and i^8 having clutch members i^9 and i^{10} which operate, respectively, in connection with the clutch members i^5 and i^6 . The drive wheels i^7 and i^8 are rotatably mounted on the shaft f , and the wheel i^8 is connected with the wheel d^6 on the shaft d^2 by a belt j , and the wheel i^8 is connected with the wheel d^7 on the shaft d^2 by a twisted belt j^2 . With this construction, the belt j will turn the shaft d^2 in one direction and the belt j^2 in the opposite direction and this will reverse the direction of the movement of the drum b as will be readily understood.

The rod i is provided between the brackets e with two spaced stops k and k^2 and mounted on said rod between said stops and movable longitudinally thereon is an arm k^3 having an opening k^4 through which the shaft f passes, and said arm is provided with an ear k^5 through which is passed a rock pin k^6 provided with a head k^7 which is made in the form of a half nut and is provided with an arc-shaped thread k^8 adapted to operate in connection with the threads on the shaft f . Mounted on the rock pin k^6 is a disk m having a radial finger m^2 which operates in connection with spiral springs n secured to hangers n^2 connected with a rod n^3 mounted parallel with the shaft f in the brackets e .

The operation will be readily understood from the foregoing description, when taken in connection with the accompanying drawing and the following statement thereof.

It will be understood that power may be applied to the wheel g^2 in any desired manner, and in practice, the lever g^7 is manipulated to throw the hub of said wheel into engagement with the clutch member g as shown in Fig. 4, and the shaft f will be turned by said wheel. The arm k^3 with its ear k^5 , and the part k^6 with its head k^7 , and the disk m with its finger m^2 , operating in connection with the spring n , form a tripper device for manipulating the rod i and the clutch members i^5 and i^6 are for the purpose of reversing the shaft d^2 , and the direction of rotation of the drum b . Supposing the parts to be in the position shown in Figs. 1 and 6 when the shaft f is started. In this position of said parts the shaft d^2 will be operated by the belt j^2 and the tripper arm k^3 will move to the right until it strikes the stop k^2 at which time the finger m^2 will

strike the spring n of the hanger n^2 and the pin k^6 will be rocked and the head k^7 will be also moved so that the thread k^8 therein will engage the reverse thread on the shaft f . When the arm k^3 strikes the stop k^2 the rod i is moved longitudinally to the right as is also the yoke i^3 and the clutch members i^5 and i^6 . This operation throws the clutch member i^6 out of engagement with the wheel i^8 and throws the clutch member i^5 into engagement with the wheel i^7 and the belt j^2 is thrown out of operation while the belt j is thrown into operation, and the direction of rotation of the shaft d^2 and the drum b is reversed, as will be readily understood. As the tripper device moves back to the left and strikes the stop k on the rod i , the above operation is reversed, the rod i is moved to the left and the belt j is thrown out of operation and the belt j^2 into operation and the direction of rotation of the shaft d^2 and the drum b is again reversed. It will be understood that the operation of the tripper device and the longitudinal movement of the rod i in opposite directions thereby are automatic and continue as long as the shaft f is rotated, and the direction of rotation of the shaft d^2 and of the drum b is reversed at regular intervals, and this operation continues as long as the machine is in operation.

The reverse movement of the drum b operates, as will be understood, to thoroughly stir and agitate the garments or articles therein more completely than if the rotation of said drum was in one direction only.

When the articles within the drum are thoroughly washed they are taken therefrom and passed through the wringer h and said wringer is operated by manipulating the lever g^7 so as to throw the drive wheel g^2 into engagement with the gear g^5 , and in this operation the shaft f is not rotated.

In the use of this machine the receptacle a is filled or partially filled with water as shown at o so that the drum b will be entirely covered thereby, and my invention is not limited to the construction of the drum b and any suitable device of this class may be employed, all that is necessary being to provide a drum through which the water is free to pass and in which the articles to be washed may be placed, and from which said articles may be removed and passed through the wringer when desired; and changes in and modifications of the other features of construction herein shown and described may be made, within the scope of the appended claims, without departing from the spirit of my invention, or sacrificing its advantages.

Having fully described my invention, what I claim as new and desire to secure by Letters Patent, is:

1. In a reversing mechanism of the class described, a rotary member, a gear connected

therewith, a shaft mounted over said gear and parallel with said rotary member, a pinion and two drive wheels secured on said shaft, said pinion meshing with said gear, a 5 power shaft mounted parallel with said rotary member, two drive wheels loosely mounted on said power shaft, means for operatively connecting the gear wheels on the first named shaft with those on the 10 power shaft, two clutch devices longitudinally movable on said power shaft and adapted to engage the gear wheels thereon, and means whereby the operation of the power shaft will operate said clutch devices 15 and move the same in opposite directions and reverse the movement of said rotary member.

2. In a reversing mechanism, a rotary member, a gear connected therewith, a shaft 20 mounted parallel with said member, a pinion secured to said shaft and meshing with said gear, two drive wheels secured on said shaft, a power shaft mounted parallel with said rotary member, two drive wheels loosely 25 mounted on said power shaft and corresponding with the first named drive wheels,

means for operatively connecting the drive wheels on the power shaft with those on the first named shaft, two clutch devices longitudinally movable on said power shaft and 30 adapted to engage the drive wheels thereon, said power shaft being also provided with reverse threads, a tripper rod mounted parallel with said power shaft and provided with spaced stops, a trip device mounted 35 longitudinally of said rod and through which said shaft passes, another rod mounted parallel with said power shaft, a spring attachment connected with said rod and having a spiral spring in connection with which 40 the tripper device operates, and means whereby the operation of said tripper device will operate said clutch devices.

In testimony that I claim the foregoing as my invention I have signed my name in 45 presence of the subscribing witnesses this 26th day of October, 1911.
